UNITED STATES PATENT OFFICE

MELVIN D. COMPTON, OF NEW YORK, N. Y., ASSIGNOR TO FRANK FULLER, OF NEW YORK, N. Y.

ACETYLENE-GAS GENERATOR.

No. 819,980.

Specification of Letters Patent.

Patented May 8, 1906.

Application filed October 3, 1901. Serial No. 77,344.

To all whom it may concern:

Be it known that I, MELVIN D. COMPTON, a citizen of the United States, residing at New York city, in the county and State of New York, have invented a certain new and useful Acetylene-Generator, of which the following is a specification.

The objects of the present invention are to provide for the removal of the residuum after the liberation of the gas by immersion of the carbid in water, to provide an automatic, reliable, and efficient generator, and to provide a generator which may be recharged without interfering with the operation of generating gas.

To these and other ends hereinafter set forth the invention, stated in general terms, comprises a gas-holder and its fluid-receptacle provided with means whereby calcium carbid is fed into the fluid, whereupon its gas is liberated, and the residuum is then fed or carried from the fluid and deposited in any suitable place or receptacle.

The invention further comprises the improvements hereinafter described and claimed.

The nature, characteristic features, and scope of the invention will be more fully understood from the following description, taken in connection with the accompanying drawings, forming part hereof, and in which—

Figure 1 is a view principally in central section illustrating a generator embodying features of the invention; and Fig. 2 is a view, partly in section, illustrating a carbid-carrier suitable for use in connection with the generator shown in Fig. 1.

In the drawings, 1 is a receptacle for the fluid, which is usually water, and in which the carbid is submerged or immersed so as to liberate its gas.

2 is a gas-holder operatively arranged in respect to the receptacle 1. Within the receptacle 1 is arranged a conveyer 3, to which the carbid is fed and which serves to convey it to the liquid contained in the receptacle 1. Means are provided for retaining the carbid in the fluid sufficiently long to insure the liberation of the gas. To this end I have illustrated a portion of the conveyer 4 as movable in respect to or pivotally connected with the other portion of the conveyer. When the end 4 of the conveyer is lifted up into the position shown by dotted lines in Fig. 1, the car-

bid is detained at the union of the parts 3 and 4, or, in other words, near their point of pivotal connection long enough to permit of the liberation of its gas. When the end 4 is placed at the same inclination as or in line with the part 3, the residuum travels the length of the conveyer and is by it conducted to a suitable place for removal from the receptacle 1. For example, is it conveyed into position for being taken up by the elevator 5, which in its turn serves to deposit the residuum in any convenient place, for example, into a vessel containing water or into any other suitable repository. As shown, the elevator 5 is arranged in a suitable well which communicates with the interior of the vessel 1, so as to permit of the passage of the residuum. The lower portion of the vessel 1 may be made inclined, as shown, and the lower portion of it may be provided, if desired, with a removable screw-plug 6, so as to afford means for cleaning it out, if desired. The conveyer 3, or rather so much of it as extends outside of the receptacle 1, is, in effect, a conduit and contains fluid. To feed the carbid to the conveyer, use may be made of the pocketed wheel 7, which is rotatably mounted in a suitable casing. This casing is equipped with a feed-chute 8, which serves to deliver carbid to the wheel 7. The upper end of the chute 8 is sealed by provisions, as 9, fitted with a suitable flanged cover locked by a lever 10. By sealing up all of the means and passages by which the carbid is fed to the conveyer it is impossible for gas to escape through them, and the gas is when generated delivered into the holder 2, from which it may be led away for use, for example, by means of a pipe 11. As illustrated in the drawings, the lever 10 is arranged to swing about a vertical axis which carries a three-way valve, so that when the lever is thus operated the interior of the part 8 is connected with a vent 12, which serves to permit of the entrance and exit of sufficient air to permit of the withdrawal and replacing of the cover. When the cover is replaced and locked by the lever, the passage to the vent is closed and the interior of the part 8 is connected by the pipe 13 with the gas-pipe 11, so that if any gas reaches the part 8 it is led by the pipe 13 to the gas-pipe 11.

Obviously the elevator and the movable part 4 may be operated in a variety of ways

or even by hand. However, I have illustrated means for effecting their automatic operation through the rise and fall of the part 2. For this purpose the part 2 is provided 5 with pivotal spring-controlled pawl-bars 14 and 15. The pawl-bar 15 serves when the gas-holder 2 rises to mesh with the teeth of a ratchet-wheel 16 and turn it, and thus cause the elevator to lift the residuum. The pawl-bar 10 14 meshes with the teeth of a ratchet-wheel 17 when the gas-holder 2 falls and turns it, thereby turning the bucket-wheel 7.

18 represents a spherical carbide-carrier, which is perforated or otherwise provided 15 with openings and which is made in sections normally held together, as by catches or the like 19. The carbide is placed in these carriers, and it is obvious that their form is well adapted to permit them to travel through the 20 conveyer and that they are also well adapted to permit of the escape of the gas and to retain the residuum.

The mode of operation of the generator may be described as follows: A supply of carbide 25 is fed to the conveyer 3, and when the machine is equipped as illustrated in the drawings this is accomplished by filling a number of the carriers with carbide and introducing them into the part 8. As the supply of gas 30 from the holder is consumed it will fall, and in falling it rotates the bucket-wheel, as described, so that the latter feeds the carriers to the conveyer. In falling, the holder 2 brings a suitable arm or projection 20 into engagement with an arm or projection 21, connected with the part 4, as shown by dotted lines on Fig. 1. In this way the movable part of the conveyer is properly positioned 35 for detaining the carbide in the fluid long enough to insure the generation of the gas. The gas is generated, reaches the holder 2, and lifts it. As it lifts, the arm 21 permits the part 4 to come into alignment with the part 3 by its own weight, so that the residuum, together with the carrier 19 when present, travels into position for being taken up by the 40 elevator. The rise of the holder also actuates the elevator in the manner described, 45

and the residuum is thus taken away from the machine. This operation is of course automatically repeated and fresh supplies of carbide may be introduced without interfering with it by reason of the provisions which control the outlet to the pipe 13 and to the vent 12. 50

It will be obvious to those skilled in the art to which the invention relates that modifications may be made in details without departing from the spirit thereof. Hence I do not limit myself to the precise construction and arrangement of parts hereinabove set forth 55 and illustrated in the accompanying drawings; but,

Having thus described the nature and objects of the invention, what I claim as new, and desire to secure by Letters Patent, is— 60

1. The combination in a gas-generating apparatus, of a fluid-receptacle, a gas-holder operating in conjunction therewith and having an outlet, means for automatically feeding predetermined quantities of gas-generating material, a sealed delivering-chute, whereof one end communicates with said means and whereof the other end is capable of being elevated to detain the gas-generating material in the fluid-receptacle, a well communicating 70 with the fluid-receptacle and with said chute, means operatively disposed in said well for removing the residuum, and a three-way valve communicating with said chute and adapted for establishing communication with 75 the atmosphere and with said outlet, substantially as described.

2. The combination in an acetylene-gas-generating plant, of a main gas-pipe, a sealed carbide-delivering chute, and a three-way 80 valve communicating with said chute and adapted for establishing communication with the atmosphere and with the gas-pipe, substantially as described.

In testimony whereof I have hereunto 85 signed my name.

MELVIN D. COMPTON.
